R. H. ROGERS

MEANS FOR EXAMINING RAPIDLY MOVING OBJECTS

Filed April 24, 1924

Inventor:
Robert H. Rogers,
by *Franklin S. Lunt*
His Attorney.

UNITED STATES PATENT OFFICE.

ROBERT H. ROGERS, OF ALPLAUS, NEW YORK, ASSIGNOR TO GENERAL ELECTRIC COMPANY, A CORPORATION OF NEW YORK.

MEANS FOR EXAMINING RAPIDLY-MOVING OBJECTS.

Application filed April 24, 1924. Serial No. 708,786.

To all whom it may concern:

Be it known that I, ROBERT H. ROGERS, a citizen of the United States, residing at Alplaus, in the county of Schenectady, State of New York, have invented certain new and useful Improvements in Means for Examining Rapidly-Moving Objects, of which the following is a specification.

My invention relates to means for examining rapidly-moving objects, and has for its object the provision of a simple, reliable, and compact device whereby a critical examination can be made of a rapidly moving object.

More specifically my invention relates to means for examining an object moving at a speed which is so high that it is impossible to examine the object in the usual manner with any degree of exactness. My invention is particularly applicable in examining objects having a rapid rotary motion such, for example, as the teeth of a rapidly rotating gear. It may also be used in observing objects having rapid oscillatory motion, or any motion such that the object passes in rapid succession through a given position.

In carrying out my invention, I provide in a compact unitary structure a source of light for illuminating the object, a dial provided with an aperture through which the object may be observed, a motor for rotating the dial, and means for regulating the speed of the dial so that when the object passes through a given position it can be observed through the aperture.

For a more complete understanding of my invention reference should be had to the accompanying drawing, the single figure of which is a perspective view of means for examining rapidly moving objects embodying my invention and showing also its application in observing the teeth of a rapidly rotating gear.

Referring to Fig. 1 of the drawing, in carrying out my invention in one form I provide a suitable source of light 10, which is shown as comprising a well known form of electric flash light provided with an electric light bulb 11 and a suitable reflector 12. Preferably the bulb 11 is energized through insulated conductors 13 from a suitable electric supply source having a greater capacity

than the dry cells commonly used with flash lights, such as a storage battery. The electric light bulb 11 may also be adapted to be energized from the usual lighting circuit. Secured to the handle or barrel 14 on which the bulb 11 and reflector 12 are mounted is an electric motor 15, preferably having a strong series characteristic, which is energized through insulated conductors 16 from a suitable electric source of supply. This motor may conveniently be secured to the handle 14 by means of a U-shaped strap 17 passing around the handle 14 and secured by screws 18 to a block 19 between which and the curved portion of the strap the handle 14 is securely held. The motor 15 is secured to the upper ends of the strap by means of screws 20 and as shown is secured to the strap so that its axis of rotation is at an angle with the beam of light 21 emitted from the bulb 11. Preferably the axis of rotation of the motor intersects the beam of light a short distance from the light source.

A disc 23 made of opaque material, such as a metal, is rigidly secured to the shaft 24 of the motor. This disc is provided with two apertures 25 and 26 oppositely disposed near its periphery. On the stator 27 of the motor is mounted a semicircular shield 28, made of a suitable opaque material which may be metal. This shield 28 is provided with an aperture 29 of substantially the same size as the apertures 25 and 26. To assure a clear unobstructed view through them, the various apertures in the shield 28 and disc 23 are placed a distance from the axis of rotation of the motor which is somewhat greater than the outside dimension of the motor stator with reference to the axis of rotation.

For the purpose of regulating the speed of the disc 23 as it is driven by the motor, a brake screw 30 is provided. This screw is mounted in the block 19 and has its end suitably beveled and bearing against a spring arm 31 which is secured at its lower end to the block 19. Secured to the upper end of arm 31 is a pad 31^a of leather or other suitable braking material which may be brought into engagement with the disc to exert varying degrees of pressure by advancing or retracting the screw. In this

manner any desired speed of the disc may be obtained. Obviously any suitable means may be used for regulating the speed of the disc, for example, an adjustable rheostat may be provided in the circuit of the driving motor 15.

In using the device, as for instance in observing the teeth of a rapidly moving gear 32, the device is held by means of the handle 14 at such distance from the particular tooth, for example the tooth 33, which is to be observed, that the tooth is sufficiently illuminated and can be observed when either of the apertures 25 or 26 comes directly in front of aperture 29. As shown, the line of sight 34 from the eye 35 of the observer passes through the apertures 26 and 29, when they are in alinement, to the tooth 33. The speed of the disc 23 is now regulated by means of the brake screw 30 so that at the same instant that the tooth 33 reaches the position shown in the drawing either aperture 25 or aperture 26 is in front of aperture 29 so that light reflected from the tooth is received by the observer. Any image, as is well known, is retained by the eye for an appreciable interval and before one image fades, the tooth 33 will again reach the position shown in the drawing, after completing a revolution, whereupon a second image is formed, the opposite aperture of the dial being at that time in front of the aperture 29.

A rapid succession of images of the gear tooth being investigated are thus flashed to the eye of the observer so that the tooth has the appearance of being stationary and can, therefore, be critically examined while in rapid motion. In case it is desired to observe another tooth, the device is moved until the line of sight 34 is directed on that tooth. This device also is a very sensitive means of observing any variation in speed. For example, if the speed of the gear 32 should vary even slightly it will be manifested by an apparent slow rotary movement of the tooth 33 in one direction or the other depending on the direction of speed variation. Small variations in speed which may not be accurately measured or even perceived by the usual tachometer can be readily observed in this manner.

It will be observed that while the gear wheel is making one complete revolution in order to bring the tooth 33 again into position to be examined, the dial 23 makes a half revolution so as to bring the opposite aperture into position to allow light reflected by the tooth to be received by the observer. To provide for wide speed ranges it is contemplated that various dials having different numbers of apertures may be provided. For example, if it is desired to examine the tooth of a gear moving at one half the speed of the gear 32 than a dial having a

single aperture will be used in the place of the dial 23. While if it is desired to examine a gear having twice the speed of gear 32 then a dial having four apertures equally spaced will be used. In this manner objects having wide variations in speed can be observed with a motor having a moderate speed range. In each case, of course, the accurate adjustment of the speed of the dial will be made by means of the screw 30.

It will be observed that my invention is portable and hence is particularly adapted for examining objects which are not readily accessible such as the gears and other parts of machinery in operation.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States is:

1. A portable device for examining rapidly moving objects comprising the combination in a unitary structure of a handle member, a source of light on said handle member, a dial provided with an aperture, means on said handle for rotating said dial, and means for regulating the speed of said dial.

2. Apparatus for examining a rapidly moving object passing periodically through a given position comprising the combination in a unitary structure, of a handle member, a source of light on said handle member, a reflector therefor, a dial provided with an aperture through which an object illuminated from said source may be observed, a motor on said handle member for rotating said dial, and means for regulating the speed of said dial so that said aperture is in a given position when said object passes through a given position whereby said object can be examined through said aperture.

3. Apparatus for examining rapidly moving objects comprising a handle member, a source of light on said handle member, a reflector for said source of light, a motor mounted on said handle member, a dial driven by said motor, said dial being provided with an aperture through which an object illuminated from said source may be observed, and means for regulating the speed of said dial so that light from said source is reflected by said object through said aperture when said aperture is in a definite position.

4. Apparatus for examining rapidly moving objects comprising a handle member, a source of light on said handle member, a reflector for said source of light, an electric

motor mounted on said handle member, a dial driven by said motor, said dial being provided with an aperture through which an object illuminated from said source may be observed, and a brake member cooperating with said dial whereby the speed of said dial can be regulated so that light from said

source is reflected by said object through said aperture when said aperture is in a definite position.

10

In witness whereof, I have hereunto set my hand this 23rd day of April 1924.

ROBERT H. ROGERS.
